UNITED STATES PATENT OFFICE.

SIMON LAKE, OF BRIDGEPORT, CONNECTICUT.

PNEUMATIC TORPEDO-FIRING APPARATUS.

SPECIFICATION forming part of Letters Patent No. 709,335, dated September 16, 1902.

Application filed January 30, 1902. Serial No. 91,871. (No model.)

To all whom it may concern:

Be it known that I, SIMON LAKE, a citizen of the United States, and a resident of Bridgeport, in the county of Fairfield and State of Connecticut, have invented certain new and useful Improvements in Pneumatic Torpedo-Firing Apparatus, of which the following is a specification.

This invention relates more particularly to pneumatic apparatus for discharging self-propelled torpedoes from war vessels, and is designed especially for use in connection with submarine torpedo-boats, in which the firing apparatus should be fully controlled by a gunner stationed in the most favorable position for ascertaining the direction and distance from such vessel of the object at which the torpedo is to be discharged and in which also it is of the utmost importance that the entrance of external water through the torpedo-tubes should be prevented during submergence and that proper safeguards should be provided to prevent the premature firing of the torpedoes, so as to endanger the safety of the vessel and its occupants.

To this end the invention consists partly in devices located within the conning-tower or turret of the boat for controlling the torpedo-firing apparatus, partly in inboard and outboard caps for closing, respectively, the breech and muzzle of the torpedo-tube and means for maintaining the one closed while the other is opened for the introduction or discharge of the torpedo, partly in means for maintaining the torpedo locked within its tube until both caps of the latter are in their respective operative or firing positions, partly in means for locking a torpedo in the firing tube until the expulsive medium employed in ejecting the same produces in said tube a predetermined minimum pressure to cause the disengagement of such locking mechanism for the release of the torpedo, and partly in certain other features which will hereinafter appear.

In the annexed drawings, in which the present improvements are shown embodied in a submarine torpedo-boat, Figure 1 is a sectional elevation of the stern portion of the boat, illustrating the apparatus embodying my invention and disclosing a portion of the

conning-tower or turret containing the valves by which the pneumatic portion of the torpedo-discharging apparatus is controlled. Fig. 2 is a similar view, upon a larger scale, 55 showing the torpedo-tube and the adjacent portions of the apparatus set for the introduction of a torpedo from the interior of the boat and showing also the forward portion of a torpedo about to be placed in position in 60 said tube. Fig. 3 is a view similar to Fig. 2, but indicating the several operative parts disposed in readiness for the discharge of the torpedo. Fig. 4 is an external view of the parts shown in Fig. 2 with the stern or outboard end portion of the torpedo-tube in section. Fig. 5 is an end elevation of the apparatus viewed from the inner end. Fig. 6 is an outboard end elevation showing the stern of the boat and the sea-cap normally 70 closing the muzzle of the torpedo-tube. Fig. 7 is a sectional elevation, upon an enlarged scale, showing one of the slings and the track by which reserve torpedoes are supported within the boat. Fig. 8 is a sectional elevation, upon a still larger scale, showing the 75 torpedo-locking devices; and Fig. 9 a bottom plan of the same. Fig. 10 is a vertical section of the main air-supply pipe with its gate-valve and the cylinder and piston constituting a motor by which such valve is operated, and Fig. 11 is a sectional elevation showing one of the locking devices for maintaining the sea-cap closed while the inboard cap is unseated.

The hull A of the boat is provided with a conning-tower or turret B, which is isolated from its interior by means of the floor C, having the hatch D to establish communication between said portions of the boat which are 90 otherwise separated by the water-tight wall or partition formed by the said floor C. The erection of the conning-tower wholly above the hull enables the gunner or lookout stationed therein to see the enemy, even in a 95 seaway, while the entire hull remains submerged, so that a very small target is offered for the enemy's guns, while the separation of the conning-tower or turret from the remainder of the boat by a water-tight wall or partition insures the safety of the other occupants, even in case the projecting portion is 100

struck and pierced by a projectile, the filling of the conning-tower not endangering the foundering of the boat.

The torpedo-tube *a* is disposed longitudinally of the boat, as usual, and is shown arranged slightly above the axis or center line of the "cigar-shaped" hull and somewhat below the top of the superstructure *E*, in which are contained the firing-tank *F* and the main air-tank *G*, from which latter may be drawn the air for charging the firing-tank preferably for each torpedo-expelling operation. The torpedo-tube is provided with a removable outboard or muzzle cap *b* and a similar inboard or breech cap *c*, the one pivoted to open downwardly and the other to open upwardly, respectively, and each being provided with a hinge *2*, bolted to a bracket *3*, secured to the tube *a*, with an interposed yielding or elastic packing *4*, preferably of soft rubber, a gasket *5*, of similar material, being interposed between the end of the tube *a* and its respective cap. By the employment of the yielding packings *4* under the hinges *2* the application of external force, whether of the external water upon the outboard or sea cap *b* or of the clamp-screw *6*, carried by the transversely-pivoted yoke *7*, pressing upon the segmental bearing-ribs *8*, forming external seats therefor upon the inboard cap *c*, insures an equal distribution of pressure upon the opposed members, and thus prevents the leakage between the same, which has been liable to occur by reason of the uneven strains due to the rigidity of hinges such as have been commonly employed heretofore in similar positions. The sea-cap *b* is provided with a lateral arm *d*, extending beyond the pintle of the hinge *2* and connected, by means of a short link *e*, with a suitably-guided cross-head upon the adjacent end of the actuating-rod *f*, passing through stuffing-boxes in the air-cylinder *g* and attached to the piston *h* in said cylinder. The rod *f* is shown provided upon its inner end, adjacent to the breech of the torpedo-tube, with a fixed sleeve or collar *i*, slidably fitted to a stationary inboard bearing *j*, depending from the tube *a* and having rearward of said bearing a square thread formed therein, to which is fitted the internally-threaded hub of a hand-wheel *k*, constituting a thrust-collar for preventing the premature or accidental retraction of the rod *f* for opening the sea-cap. The inner end of the tube *a* is further provided with a depending socket-piece *l*, within which is fitted a stop-plug *m*, having a fixed collar *n*, between which and the exterior of the tube *a* is preferably interposed a spring *o*, operating to yieldingly maintain the lower end of the plug normally in the path of movement of the sleeve *i* upon the rod *f*, as shown in Fig. 11, when the breech-cap is open. The lower portion of the stop-plug *m* is beveled upwardly and inwardly for engagement with the adjacent end of a tappet-rod *p*, journaled

slidably in a lateral arm of the socket-piece *l* and having its opposite end projected normally in the path of the laterally-extending portion of the inboard cap *c*. As this cap is closed upon the adjacent end of the tappet-rod the latter is forced into engagement with the beveled end of the plug *m* and presses the same upward in opposition to the spring *o*, so as to withdraw the overhanging or latch portion from the closely-adjacent end of the sleeve *i* and rod *f*. The thrust-collar *k* being now unscrewed from the sleeve *i* and compressed air being admitted into the cylinder *g* through the air-pipes *r* and *r'* from the firing-tank *F* and the pipe *s* being simultaneously connected with the outwardly-leading pipe *s'* for releasing any air contained in the forward end of the cylinder by means of the four-way valve *q* in the conning-tower, the piston *h* is forced to the forward end of the cylinder *g*, and the rod is thus actuated to open the sea-cap against the external water-pressure. By reference to Figs. 3 and 5 it will be observed that when the outboard cap *b* is open the rod *f* projects beyond the flange of the inboard cap *c*, and thus effectively prevents the lowering of the swinging yoke *7*, which is pivoted to the tube *a* concentrically with the curved bearing-rib *8* to release the inboard cap, and it is therefore to be understood that both caps can never be open at the same time, so as to endanger the swamping of the boat by admission of water through the torpedo-tube.

The torpedo *T* is shown provided with an annular external shoulder offered by the wall of a small conical or tapering aperture or recess *t* in its outer surface, which is preferably formed in a small casting secured to the exterior of the torpedo, and this recess is entered by the beveled or conical end of a locking-pin *u*, formed upon or secured to the piston *v* of a cylinder *w*, attached to the under side of the torpedo-tube and having its adjacent end in communication with the interior of the same by means of the holes or ports *x*. The lower end of the pin *u* is beveled rearwardly and downwardly and arranged to barely clear the upper edge and the forward shouldered end 10 of a stop projection *9* upon the rod *f*, the opposite end of which projection terminates in a beveled portion 11, extending rearwardly in the direction of the sea-cap. The piston *v* is provided with guide-rods *y*, extending through the lower end of the cylinder *w* and terminating in the cross-pieces *z*, serving as handles for manually withdrawing the pin *u* from the recess *t* in opposition to the spiral springs 12, interposed upon said guide-rods between the piston *v* and the head of the cylinder *w* when a torpedo is being introduced. It is obvious that by an arrangement of parts by which the cylinder *w* is disposed upon the top of the tube *a* and assumes an inverted position the pin *u* and its attached piston *v* will gravitate into operative rela-

tion with a correspondingly-disposed external shoulder upon the torpedo, and the provision of springs 12 will thus become unnecessary for retaining such locking member in normal 5 position.

The main air-pipe 13, leading from the firing-tank F to the inboard end of the torpedo-tube *a*, as shown in Figs. 4 and 5, is provided with a gate-valve 14, of which the stem 15 is 10 attached to the piston 16, contained within a cylinder 17, disposed axially in line with said valve-stem and constituting a motor which is controlled by a four-way valve 18, located in the conning-tower and otherwise similar to 15 the valve *q*, the said valve being connected with the opposite ends of the cylinder 17 by means of air-pipes 19 and 20. By operating the valve 18 to open the gate-valve 14 air is admitted from the firing-tank F into the 20 breech end of the torpedo-tube *a*, and the outboard cap *b* having been opened by the retraction of the rod *f*, whose stop projection 9 thus assumes the position indicated in dotted lines in Fig. 8, the stern portion of the 25 torpedo *T* resists the pressure of the air behind it in the tube *a* until its intensity is sufficient to overcome the tension of the springs 12 in the communicating cylinder *w*, when the locking-pin *u* is retracted from its aperture in the exterior of the torpedo, which latter is then discharged from the tube and its 30 internal propelling machinery simultaneously set in motion in the customary manner.

As the torpedo-tube *a* is in practice always 35 free from water while the torpedo is being placed in position, whether it be introduced from the exterior while the boat is upon the surface or from the interior during submergence, it is important that provision be made 40 for admitting and expelling water to and from the same in order to permit of the introduction and discharge of the torpedo. To this end the breech portion of the tube *a* may be connected with a pipe 21, provided with a 45 three-way valve 22, from which one branch 23 leads to the exterior of the boat and another branch 24 is connected with one of the ballast-tanks, so as to restore the normal condition of stability which would be disturbed 50 by the introduction or expulsion of a torpedo or other object materially affecting the gross weight of the boat. A vent-pipe 25, controlled by a petcock 26, is also provided, preferably, in the breech-cap *c*, leading from the 55 upper portion of the tube *a*, for admitting and releasing the air displaced by or replacing the water.

In order that a reserve torpedo may be carried in convenient position in the interior of 60 the boat in addition to that which is normally housed in the tube *a*, the ceiling of that portion of the hull adjacent to the breech of the torpedo-tube is provided in the vertical plane of and parallel with the axis of said tube 65 with an overhead inverted-T rail 27, forming a track upon which are mounted two or more

carriages or trolleys, each consisting of a frame 28 and wheels or rollers 29, from which frame is suspended a sling comprising a circular band 30, formed in two pivotally-connected sections having their opposed lower ends provided with perforated ears or lugs 31, united by a clamp-bolt 32, and provided also upon opposite sides with eyes 33, by which it may be suspended by a block and tackle when 70 introducing the torpedo embraced thereby into the tube *a* or when lowered to the floor for purposes of inspection or adjustment, when such bands may rest upon their legs 34, also depending therefrom. 80

In the equipment of the boat with torpedoes while upon the surface of the water the sea-cap *b* is first opened and the torpedo introduced stern first. The sea-cap is then closed and the breech-cap *c* opened and the 85 torpedo withdrawn from the inner end of the tube *a* and suspended in the slings 30, in which it may be lowered to the floor by the use of a block and tackle by first introducing a tie-bolt 35 to connect the upper ends of 90 the sections 30 and then withdrawing the hinge-pins 36, by which they are normally suspended from the carriage. As it is impossible to open either of the caps *b* or *c* while the other remains open, it is necessary 95 to close the breech-cap *c* before opening the sea-cap *b* to receive the second torpedo, after which last-named operation the second torpedo is similarly introduced, the locking-pin *u* having been temporarily withdrawn by 100 means of the handle-bars *z* in each case, while in the latter instance such pin is released when the torpedo reaches its normal position within the tube and the pin is allowed to enter its recess *t* therein to insure 105 the proper location of the torpedo for the subsequent firing operation. The sea-cap is then closed and the thrust-collar *k* applied to its sustaining-sleeve *i* and seated firmly against the bearing *j*, which manual operation effectively prevents the effective actuation of the pneumatic portions of the apparatus while the collar *k* remains in such position. The valve 22 is then manipulated to admit external water through the pipes 21 110 and 24 to fill the otherwise unoccupied space in the tube *a*, the petcock 26 being opened for the escape of the air thereby displaced. To discharge the torpedo thus placed in position, the thrust-collar is first withdrawn from its 115 locking position, and the breech-cap being closed and the stop-plug *m* being thus withdrawn from the path of the rod *f* air is admitted to the rear end of the cylinder *g* by means of the valve *q* to force its piston to the 120 opposite end, and thereby retract the rod *f* to open the sea-cap *b*. During this operation and while the projection 9 is passing under the end of the pin *u* the torpedo is positively locked in its position thereby; but as the inclined end 11 of such projection passes under the pin the latter becomes free to yield to the 125 130

air-pressure within the cylinder *w*. The four-way valve 18 in the conning-tower is now operated to withdraw the piston and its rod to open the gate-valve 14, which establishes direct communication between the firing-tank F and the breech end of the torpedo-tube *a*. As already stated, the torpedo is not immediately expelled, but remains locked in place by the locking-pin *u* until the internal air-pressure is sufficient to force the piston *v* of the connected cylinder *w* downward in opposition to the springs 12, which are set to yield only at such a minimum pressure in the tube *a* as will cause the torpedo to assume a suitable initial speed to carry it clear of the boat to prevent subsequent collision and possible resulting disaster. The tube *a* being subsequently closed by reciprocal manipulation of the valves *q* and 18 in the conning-tower, the petcock 26 is first opened to admit air from the interior to replace the water to be drawn off, and the water replacing the discharged torpedo is then led out through the pipes 21 and 24 by suitable manipulation of the cock 22 into one of the water-ballast tanks, the equilibrium of the boat not being disturbed by such operation, after which the breech-cap may be opened and the reserve torpedo introduced, the procedure in the expulsion of which subsequent to the closing of the breech-cap is similar to that already described. Should the air-valve 14 be first actuated accidentally by the gunner, the water in the closed torpedo-tube will resist the outward movement of the torpedo, and when the pressure in such tube becomes sufficient to depress the locking-pin *u* such member is thrown into the path of reciprocation of the shoulder 10 of the stop projection 9, and thereby serves to prevent the opening of the cap *b* to release the torpedo until such pressure is relieved, when the opening of the sea-cap will act to maintain the locking-pin in operation until the cap is entirely opened for the free discharge of the torpedo.

From the foregoing description it will be observed that while the present improvement is particularly adapted to submarine torpedo-boats it has various features which are well adapted for operation in surface vessels fitted for firing torpedoes, and it is therefore to be understood that the invention is not limited to embodiment in submarine vessels only, nor is it limited to the particular construction and arrangement of parts herein shown and described, it being obvious that such matters may be widely varied without departing from the spirit of the present invention.

Having thus set forth the nature of the invention, what I claim herein, and desire to secure by Letters Patent, is—

1. In combination, a submarine boat provided with a conning-tower rising above the hull of the same and normally separated therefrom by a water-tight wall or partition

and a torpedo-tube, a compressed-air reservoir and a connection therefrom to the inner end of said torpedo-tube, and devices controlled by means within the conning-tower for admitting compressed air to the torpedo-tube for expelling a torpedo therefrom. 70

2. In combination, a submarine boat provided with a conning-tower disposed upon the exterior of and wholly above the hull of the same and normally separated therefrom by a water-tight wall or partition and a torpedo-tube, a compressed-air reservoir and a connection therefrom to the inner end of said torpedo-tube, and devices controlled by means within the conning-tower for admitting compressed air to the torpedo-tube for expelling a torpedo therefrom. 75

3. In combination, a submarine boat provided with a conning-tower rising above the hull of the same and a torpedo-tube, a compressed-air reservoir, a pipe connection from said compressed-air reservoir to the inner end of said torpedo-tube, a valve in said pipe connection, a motor the movable member of which is connected to said valve, and means within the conning-tower for controlling the operation of said motor for actuating the said valve. 85

4. In combination, a submarine boat provided with a conning-tower rising above the hull of the same and a torpedo-tube, a compressed-air reservoir, a pipe connection from said compressed-air reservoir to the inner end of said torpedo-tube, a valve in said pipe connection, a cylinder, a piston within said cylinder provided with a suitable connection with said valve, and means within the conning-tower for effecting the movement of said piston to actuate the said valve. 95

5. In combination, a submarine boat provided with a conning-tower rising above the hull of the same and a torpedo-tube, inboard and outboard caps for said torpedo-tube, mechanism for opening the outboard cap from within the boat, means connected with or applied to the inner end of said torpedo-tube to provide expulsive power for ejecting a torpedo, means within the conning-tower for operating the mechanism for opening the outboard cap of said torpedo-tube, and means also controlled from within the conning-tower for effecting the expulsion of the torpedo. 105

6. In combination, a submarine boat provided with a conning-tower rising above the hull of the same and a torpedo-tube, inboard and outboard caps for said torpedo-tube, mechanism for opening the outboard cap from within the boat comprising a cylinder and actuating-piston contained therein and connected with said mechanism, a compressed-air reservoir, a pipe connection from said compressed-air reservoir to the inner end of said torpedo-tube, a valve in said pipe connection, a second cylinder and actuating-piston contained therein and connected with said valve, and devices within the conning-tower for suc- 110

cessively operating the said pistons to first open the outboard cap and thereafter open the valve in the said pipe connection for effecting the expulsion of the torpedo from said tube.

5 7. In combination, a submarine boat provided with a conning-tower rising above the hull of the same, a torpedo-tube, inboard and outboard caps for said torpedo-tube, mechanism for opening said outboard cap from within the boat, a stop device controlled by the inboard cap for locking the outboard cap in its closed position while the inboard cap is open, a compressed-air reservoir, a pipe connection from said compressed-air reservoir to the inner end of the torpedo-tube, air-cylinders containing actuating-pistons connected, respectively, with a valve in said pipe connection and said mechanism for opening the 15 outboard cap, and means within the conning-tower for successively admitting air to said air-cylinders to first open the outboard cap and then actuate said valve to admit air to the torpedo-tube to expel a contained torpedo.

20 8. In combination, a submarine boat provided with a conning-tower rising above the hull of the same, a torpedo-tube, inboard and outboard caps for said torpedo-tube, mechanism for opening said outboard cap from within 25 the boat, a stop device for preventing the operation of said mechanism while the inboard cap is open, a locking device normally engaging a torpedo within said tube provided with means for causing it to release said torpedo 30 at a predetermined air-pressure in said tube, an air-reservoir, a valved connection from said air-reservoir to the inner end of the torpedo-tube, and means within the conning-tower for first actuating the outboard-cap-opening mechanism and then admitting air to the torpedo-tube for expelling the contained torpedo.

35 9. In combination, a submarine boat provided with a conning-tower rising above the hull of the same, a torpedo-tube, inboard and outboard caps for said torpedo-tube, a locking device normally engaging a torpedo within said tube provided with means for causing it to release said torpedo only at a predetermined 40 minimum air-pressure within said tube, mechanism for opening said outboard cap from within the boat including a stop for preventing the releasing operation of said torpedo-locking device during the opening of said outboard cap, an air-reservoir, a valved connection from said air-reservoir to the inner end of the torpedo-tube, and means within the conning-tower for first actuating the outboard-cap-opening mechanism and then admitting 45 air to the torpedo-tube for expelling the contained torpedo.

50 10. In a torpedo-boat, the combination with a torpedo-tube and outboard and inboard caps therefor, of means for preventing the opening of one of said caps while the other remains open.

55 11. In a torpedo-boat, the combination with a torpedo-tube and outboard and inboard caps therefor, of pneumatic apparatus for opening said outboard cap, and a stop device for preventing the operation of said apparatus to open said outboard cap while the inboard cap remains open.

60 12. In a torpedo-boat, the combination with a torpedo-tube and outboard and inboard caps therefor hinged thereto, a rod supported in bearings adjacent to said tube connected with said outboard cap and provided with means for moving the same to and fro for opening and closing said outboard cap, a stop device 65 serving to normally lock said rod from movement while the inboard cap is open, and a device intermediate said inboard cap and the locking device whereby the latter is caused to release said rod to permit the opening of 70 the outboard cap.

75 13. In a torpedo-boat, the combination with a torpedo-tube and outboard and inboard caps therefor, of an actuating-rod disposed parallel with said tube and connected with said outboard cap, and means for moving said rod to and fro for opening and closing said outboard cap, a locking device consisting of a transversely-movable plug normally projected into the path of movement of said actuating-rod, and a retracting device for said plug normally projecting into the path of 80 said inboard cap and operated when the latter is closed to withdraw the said plug from the path of movement of said actuating-rod.

85 14. In a torpedo-boat, the combination with a torpedo-tube and hinged outboard and inboard caps for the same, of an actuating-rod connected with said outboard cap and disposed parallel with said tube, means for moving said rod to and fro to open and close said outboard cap, and a locking device for preventing the movement of said rod while the inboard cap is open, the same consisting of a 90 socket-piece attached to the torpedo-tube and provided with a stop-plug having its projecting outer end normally lying in the path of said actuating-rod and closely adjacent to the end of the same, and beveled with an upward and backward incline, and a tappet-rod interposed between the beveled end of said plug and the path of movement of the inboard cap upon its hinge, whereby the closing of said inboard cap upon the end of said tappet-rod causes the withdrawal of said locking-plug 95 from the path of movement of said actuating-rod to permit the opening of the outboard cap.

100 15. In a torpedo-boat, the combination with a torpedo-tube, of a cap for closing one end of the same, a hinge for said cap, a rigid seat formed upon or attached to said tube, an elastic or yielding packing interposed between said hinge and its seat, means for securing said hinge to its seat, and an elastic or yielding packing interposed between the end of 105 said tube and its cap.

16. In a torpedo-boat, the combination with a torpedo-tube, of a cap for closing one end of the same, a hinge for said cap, a rigid seat formed upon or attached to said tube, an elastic or yielding packing interposed between said hinge and its seat, an elastic or yielding packing interposed between the end of said tube and its cap, and means for maintaining the said cap pressed to its seat upon the end of said tube. 70
17. In a torpedo-boat, the combination with a torpedo-tube, of a removable cap for closing one end of the same having a curved external seat, a packing interposed between said cap and the end of said torpedo-tube, and a yoke having arranged concentrically with said curved external seat a transverse pivotal connection with said tube and adapted to engage the external seat of said cap. 75
18. In a torpedo-boat, the combination with a torpedo-tube, of a removable cap for closing one end of the same having a curved external seat, a packing interposed between said cap and the end of said torpedo-tube, a yoke having arranged concentrically with said curved external seat a transverse pivotal connection with said tube and adapted to swing across the end thereof provided with said cap, and a clamp-screw carried by said yoke and adapted to engage the external seat of said cap. 80
19. In a torpedo-boat, the combination with a torpedo-tube, of a locking device for normally engaging a torpedo housed in said tube, and means actuated by a predetermined minimum pressure within said torpedo-tube for disengaging said locking device from the torpedo. 85
20. In a torpedo-boat, the combination with a torpedo-tube, of a locking-pin for normally engaging an external shoulder of a torpedo contained within said tube, a cylinder communicating with the interior of said torpedo-tube, and a piston within said cylinder and connected with said locking-pin to withdraw the latter at a predetermined minimum pressure within said torpedo-tube. 90
21. In a torpedo-boat, the combination with a torpedo-tube having a removable outboard or muzzle cap, of a locking-pin for normally engaging an external shoulder upon a torpedo contained within said tube, a cylinder communicating with the interior of said torpedo-tube, a piston within said cylinder connected with said locking-pin, and a stop device connected with said outboard cap and so constructed and arranged as to maintain the torpedo-locking device in operative position between the extreme open and closed positions of said outboard cap. 95
22. In a torpedo-boat, the combination with a torpedo-tube, and a compressed-air reservoir, of a pipe connection from said air-reservoir to the inner end of said torpedo-tube, a valve in said pipe connection, a cylinder, a piston within said cylinder having its rod operatively connected with said valve, and means for supplying motive power to said cylinder for actuating said piston to operate the said valve. 100
23. In a torpedo-boat, the combination with a torpedo-tube, and a compressed-air reservoir, of a pipe connection between said compressed-air reservoir and torpedo-tube, a gate-valve in said pipe connection, an air-cylinder disposed axially in line with said gate-valve and having a piston whose rod is directly connected with the stem of said gate-valve, and means for supplying compressed air for actuating said piston to open and close said gate-valve. 105
24. In a torpedo-boat, the combination with a torpedo-tube and a removable outboard cap therefor, of a power-operated device for opening and closing said cap, and a manual locking device for preventing the actuation of said power-operated device to open said cap, when desired. 110
25. In a torpedo-boat, the combination with a torpedo-tube and a removable outboard cap therefor, of a rod connected with said cap and extended within said boat, a stationary inboard bearing to which the inner portion of said rod is slidably fitted, and a longitudinally-movable thrust-collar upon said rod adapted to engage said inboard bearing for preventing the movement of said rod. 115
26. In a torpedo-boat, the combination with a torpedo-tube and a removable inboard cap therefor, of an overhead rail or track disposed in the vertical plane of and parallel with the axis of said tube, and torpedo-carrying slings depending therefrom. 120
27. In a torpedo-boat, the combination with a torpedo-tube and a removable inboard cap therefor, of an overhead rail or track disposed in the vertical plane of and parallel with the axis of said tube, carriages mounted upon said track, and torpedo-carrying slings removably attached to and depending from said carriages. 125
28. In a torpedo-boat, the combination with a torpedo-tube and a removable inboard cap therefor, of an overhead rail or track disposed in the vertical plane of and parallel with the axis of said tube, carriages mounted upon said rail or track, and torpedo-carrying slings attached to and depending from said carriages, said slings being formed each in two separable semi-annular sections united at the opposed ends by means of pivotal pins and by a clamp-bolt, respectively, and adapted to be separated for the reception of a torpedo. 130
29. In a torpedo-boat, the combination with a torpedo-tube and a removable inboard cap therefor, of an overhead rail or track disposed in the vertical plane of and parallel with the axis of said tube, carriages mounted upon said rail or track, and torpedo-carrying slings attached to and depending from said carriages, said slings being formed each in two

semi-annular sections 30 having the opposed ends connected at the point of suspension to the carriage, through which they are united together, by means of removable pivotal pins 36 and clamp-bolt 35, and at the opposite point of connection by means of a clamp-bolt 32, each section being also provided with a suspension-eye 33.

30. In a torpedo-boat, the combination with a torpedo-tube having removable inboard and outboard caps, of a compressed-air reservoir,

a valved pipe connection therefrom to the breech end of said torpedo-tube, and a valved pipe connection from said tube to the exterior of the boat.

Signed at Elizabeth, in the county of Union and State of New Jersey, this 23d day of January, A. D. 1902.

SIMON LAKE.
